UNITED STATES PATENT OFFICE

155,232

DESIGN FOR A BLOCK MOUNTED SET OF LETTERS AND NUMERALS

Paul A. Price, Sunnyside, N. Y.

Application February 7, 1949, Serial No. 732

Term of patent 14 years

(Cl. D64—12)

To all whom it may concern:

Be it known that I, Paul A. Price, a citizen of the United States of America and resident of Sunnyside, county of Queens, State of New York, have invented a new, original, and ornamental Design for a Block Mounted Set of Letters and Numerals, of which the following is a specification, reference being had to the accompanying drawing, forming a part thereof, in which

Fig. 1 is a front view of a block mounted set of letters and numerals, embodying my design;

Fig. 2 is a sectional side view thereof along the line 2—2 of Fig. 1; and

Fig. 3 is an end view thereof.

I claim:

The ornamental design for a block mounted set of letters and numerals, as shown.

PAUL A. PRICE.
